Inventor,
George H. Parsons,
By his Attorney
Paul A. Comiskey.

UNITED STATES PATENT OFFICE.

GEORGE H. PARSONS, OF NEW YORK, N. Y.

DOLL.

1,396,873.

Specification of Letters Patent. Patented Nov. 15, 1921.

Application filed January 31, 1920, Serial No. 355,484. Renewed September 30, 1921. Serial No. 504,495.

To all whom it may concern:

Be it known that I, GEORGE H. PARSONS, a citizen of the United States, residing at New York, in the county and State of New York, have invented certain new and useful Improvements in Dolls, of which the following is a specification.

This invention relates generally to dolls, with more particular reference to what are commonly known as "sleeping" dolls, the eye-balls of which include portions made to resemble eye-lids, said eye-balls being pivoted within the head in proper positions and so weighted that when the doll is in an upright position the eyes thereof are "open," but when the doll is tipped rearwardly to reclining position the weights operate to rotate said eye-balls to simulate closing of the eyes, as in sleep.

In the common and well-known type of "sleeping" doll, characterized as above briefly outlined, obviously, the eyes will "close" as the doll is brought to a recumbent or horizontal position. The well-known propensity of childhood for more nearly perfect simulation creates a desire for a doll which will not immediately close its eyes upon being tipped to reclining position, but the eyes of which will close gradually if while in such reclining position the doll is "rocked," after the manner of the rocking of a sleepy infant.

The trouble with most attempts to provide a "sleeping" doll in which the eyes close gradually when the doll is rocked would seem to have been the necessity for the provision of a mechanism or other apparatus within the head of the doll of such a complicated character as to make the cost of production prohibitive, so far as the average purchasing public is concerned. The principal object of the present invention, therefore, is the provision of gradually operating eye-closing mechanism of such simple construction and operation as not only to minimize the cost of manufacture of the doll head but to bring the price of the finished product within the reach of purchasers with limited means.

Incidental to the above, I have in view mechanism, which, while it will effect gradual closing of the eyes when the doll is tipped to reclining position and gently rocked, will effect immediate opening of the

eyes when the doll is returned to upright position, thus further enhancing the simulation.

My invention will be more readily understood by reference to accompanying drawings, forming a part of this specification, in which

Figure 1 is a longitudinal section, taken substantially on the line 1—1 of Fig. 2, of the head of a doll equipped with eye opening and closing mechanism embodying my invention, the doll being supposed to be in reclining or recumbent position;

Fig. 2 is a face view thereof, partly in section, and

Fig. 3 is a transverse section, taken substantially on the line 3—3 of Fig. 1.

Referring now to drawings in detail, numeral 5 designates a doll's head, which may be made in the usual manner from any one of a number of materials commonly employed for this article. This head 5 generally includes a neck portion 6 to which the body portion of the doll, generally consisting of suitably stuffed fabric, is secured, the crown of the head being initially left open for the insertion and mounting of the eye-operating mechanism, the opening being subsequently covered by the wig.

The interior side walls of the head are provided with socketed lugs 7 and 8, the sockets being adapted to receive and rotatively contain the ball-like protuberances 9 and 10 at the ends of what may be termed a U-shaped bar 11, which ball-like protuberances are also formed and finished to simulate eyes and lids. The head 5 is provided with the usual orifices in the face thereof, and all of these parts are so relatively positioned that said ball-like protuberances project into or slightly through said openings, and upon rocking of said bar 11 in the sockets cause rotation of said protuberances to simulate the opening and closing of the eyes in a common and well-known manner.

Projecting rectangularly from substantially the middle of the U-bar 11 is an arm or lever 12 having a weight 13 at the free end thereof. In the absence of any checking means, it will be apparent that when the head 5 is tipped from upright position to the position indicated in Fig. 1, the weight 13 will operate through the arm 12 to rock

the U-bar 11 and rotate the protuberances 9 and 10 to effect the simulative eye-closing movement.

To this point, I have described nothing more than what may be termed a common and well-known expedient. There are other ways of connecting the "eye-balls," and other ways of pivoting the eye-ball frame in the head. The construction, mounting and operation of the parts described is immaterial so far as the present invention is concerned.

To the rim 14 of the opening in the head 5, I clamp a pair of disks or plates 15 and 16 between which and the interior shoulder 15 provided where the nose merges into the forehead I mount a circular rod 17. Freely 20 slideable on this rod is a collar 18, from which projects a plate 19 which I have shown in the form of a disk. These parts 25 are all so positioned and adjusted that when the eyes of the doll are "open" the plate 19 is in contact with the side of the bottom of the U-bar 11, whereby, if the collar 18 is checked against the sliding movement along the rod 17, rotation of said U-bar in its 30 sockets will be checked and the doll may be tipped to recumbent position with the eyes remaining "open".

Also slidably mounted on the rod 17, between the collar 18 and the plates 15 and 16, is the looped end of a bent or curved lever 20, at the free end of which is mounted a weight 21. The loop 22 of said lever is of slightly greater interior diameter than the 35 diameter of the rod 17. By turning Fig. 1 to cause the head shown therein to assume an upright position, it will be apparent that whatever may have been the position of the loop 22 on the rod 17, the forces of gravity 40 generated by the weight 21 will be so directed by the bent or curved lever 20 to the loop 22 as to cause the latter to slip freely down the rod 17 to the position indicated in this figure. If, now, the doll is turned or tipped 45 to recumbent position, as shown in the natural position of Fig. 1, it will be apparent that the weight 13 will at once generate forces tending to rock the U-bar 11, as and for the purpose set forth. However, due to 50 the curvature of the lever 20 and the off-center suspension of the weight 21, the loop 22 will be inclined with reference to the rod 17 and frictionally engage the same with sufficient force to overcome the forces transmitted 55 from the weight 13, which, as will be apparent, tend to slide the collar 18 along the rod 17 through pressure of the U-bar against the plate 19. Therefore, if the doll after having been turned to recumbent position 60 is permitted to remain in a condition of rest, said U-bar will be checked against rotation and the eyes will not "close."

It will be seen that the lever 20 constitutes the rod of a pendulum of which the weight 65 21 is the bob, and is adapted to oscillate lat-

erally in addition to having sliding movement along the rod 17. It will furthermore be apparent that if the now recumbent doll is rocked, after the manner of the rocking of a child, the lever 20 will be oscillated after the manner of a pendulum by the weight 70 21. The consequent lateral oscillation of the loop 22 on the rod 17 intermittently relieves the frictional forces which check sliding movement of said loop on said rod to a degree at which they are overcome by the 75 forces transmitted from the weight 13, whereby, upon oscillation of the lever 20, the loop 22 will be forced step-by-step along said rod 17, permitting movement therewith of the collar 18, movement of which, in turn, permits a corresponding step-by-step rotation of the U-bar 11 and the consequent gradual "closing" of the eyes.

It will be seen that when the doll is returned from a recumbent to an upright position, the U-bar is free to be returned under action of the weight 13 to the position indicated in Fig. 1, wherefore the eyes will immediately "open." Furthermore, as has been 85 explained, when the doll is returned to upright position, the curvature of the lever 20 which results in off-set suspension of the weight 21 and which so directs the forces generated by said weight as to effect the 90 frictional engagement between the loop 22 and the rod 17, now so directs the forces of said weight as to permit return of said lever and said loop to the positions indicated in Fig. 1 without rocking and without interruption of movement.

With the checking plate 19 of suitable size and contour, it would probably make little if any difference, mechanically, whether or not the collar 18 were rotatable as well as 105 slideable on the rod 17. However, it is doubtless preferable that said collar be held against rotation and said plate, therefore, against oscillation. For this purpose, I have shown a relatively small guide-rod 23, 110 mounted parallel to the rod 17 and passing through the collar 18 which is also slideable on the same. In this and in other well-known ways said collar may be held against rotation and yet be freely slideable on the rod 115 17. I have also shown a lug 24 which provides a stop against which the weight 13 is adapted to impinge, thus checking rotation of the U-bar when the eyes are in "open" position.

Many modifications and minor details of my improved doll will doubtless readily suggest themselves to those skilled in the art to which it appertains, and I therefore do not desire to limit myself to the specific construction herein shown and described.

I claim:

1. In a doll's head, the combination, with means for automatically turning the eye-balls thereof when said head is tipped rear-

120

wardly from an upright to a substantially horizontal position, to simulate the closing of the eyes, said means operating to return said eye-balls to and yieldingly retain the same in their initial positions when said head is returned to upright position, of means for checking operations of said turning means, and means operated by the lateral rocking of said head while in substantially horizontal position to intermittently and momentarily release said checking means.

2. In a doll's head, the combination, with means for automatically turning the eye-balls thereof when said head is tipped rearwardly from an upright to a substantially horizontal position, to simulate the closing of the eyes, said means operating to return said eye-balls to and yieldingly retain the same in their initial positions when said head is returned to upright position, of means frictionally operable to check operation of said turning means when said head is at rest in said substantially horizontal position, and means operated by the lateral rocking of said head in such position to intermittently relieve at momentary intervals the frictional resistance of said checking means.

3. In a doll's head, the combination, with means for automatically turning the eye-balls thereof when said head is tipped rearwardly from an upright to a substantially horizontal position, to simulate closing of the eyes, said means operating to return said eye-balls to and yieldingly retain the same in their initial positions when said head is returned to upright position, of a movable and yieldingly held stop for checking operation of said turning means, and means operated by the lateral rocking of said head while in said substantially horizontal position to intermittently and momentarily release said stop.

4. In a doll's head, the combination, with means for automatically turning the eye-balls thereof when said head is tipped rearwardly from an upright to a substantially horizontal position, to simulate closing of the eyes, said means operating to return said eye-balls to and yieldingly retain the same in their initial positions when said head is returned to upright position, of a movable and frictionally held stop for checking operation of said turning means, and means operated by the lateral rocking of said head while in said substantially horizontal position to intermittently relieve at momentary intervals the frictional resistance of movement of said stop.

5. In a doll's head, the combination, with means for automatically turning the eye-balls thereof when said head is tipped rearwardly from an upright to a substantially horizontal position, to simulate closing of the eyes, said means operating to return said eye-balls to and yieldingly retain the same in their initial positions when said head is returned to upright position, of a guide-rod, a stop slidably mounted on said rod and in initial position checking operation of said turning means, means yieldingly checking said stop against sliding movement on said rod, and means operated by the lateral rocking of said head while in substantially horizontal position to intermittently and momentarily release said stop-checking means.

6. In a doll's head, the combination, with means for automatically turning the eye-balls thereof when said head is tipped rearwardly from an upright to a substantially horizontal position, to simulate the closing of the eyes, said means operating to return said eye-balls to and yieldingly retain the same in their initial positions when said head is returned to upright position, of a guide-rod, a stop slidably mounted on said rod and in initial position checking operation of said turning means, means also slid- 80
able on said rod for frictionally checking said stop against sliding movement, and means operated by the lateral rocking of said head while in substantially horizontal position to intermittently relieve at momentary intervals the frictional resistance of said stop-checking means.

7. In a doll's head, the combination, with means for automatically turning the eye-balls thereof when said head is tipped rearwardly from an upright to a substantially horizontal position, to simulate closing of the eyes, said means operating to return said eye-balls to and yieldingly retain the same in their initial positions when said head is returned to upright position, of a guide-rod, a stop slidably mounted on said rod and in initial position checking operation of said turning means, a lever loosely pivoted on said rod whereby said lever has 100 both sliding and oscillatory movements thereon, and a weight at the free end of said lever, the latter being bent for off-center suspension of said weight.

In testimony of the foregoing, I have 115 hereunto set my hand in the presence of two witnesses.

GEORGE H. PARSONS.
